UNITED STATES PATENT OFFICE

2,447,198

STARTER FOR INTERNAL-COMBUSTION ENGINES

Donald L. Miller, Pine City, N. Y., assignor to
 Bendix Aviation Corporation, South Bend, Ind.,
 a corporation of Delaware

Application May 3, 1945, Serial No. 591,655

5 Claims. (Cl. 290—38)

1

The present invention relates to a starter for internal combustion engines and more particularly to that type in which operative engagement of the drive is maintained until the engine is reliably self-operative.

It is an object of the present invention to provide a novel engine starter in which complete disengagement of the drive is dependent upon shifting the motor armature to a decentered position with respect to the field.

It is another object to provide such a device in which means under the control of the operator are provided for shifting the armature into decentered position and positively holding it in such position in order to prevent undesired engagement of the gearing due to accelerational or gravitational forces of the vehicle on which the drive may be mounted.

It is another object to provide such a device in which the control of the decentering means for the motor armature is combined with the control of the starting motor switch.

Another object is to provide such a device incorporating means for yieldably holding the motor armature in centered position during the starting operation.

Further objects and advantages will be apparent from the following description taken in connection with the accompanying drawing, in which:

Fig. 1 is a side elevation partly in section of a portion of a starting motor and control mechanism therefor comprising a preferred embodiment of the invention, the remaining elements of the starting system being indicated diagrammatically;

Fig. 2 is a similar view of the opposite end of the starting motor with the drive mounted thereon; and

Fig. 3 is a detail in perspective, partly broken away, of the overrunning clutch assembly.

This application has been divided, and the subject-matter of the novel starter gearing with normally disengaged over-running clutch has been incorporated in the divisional application of Donald L. Miller, Serial Number 665,704 filed April 29, 1946.

In Fig. 1 of the drawing there is illustrated a starting motor 1 having an armature shaft 2 which is slidably journaled in the frame of the starting motor whereby it may be moved longitudinally so as to decenter the armature with respect to the motor field. Means for energizing the starting motor are shown comprising a battery 3 grounded at 4 and connected by a lead 5

2

to one terminal 6 of a starting switch indicated generally by numeral 7. A second terminal 8 of the starting switch is connected by a lead 9 to the starting motor, indicated diagrammatically at SM, which is grounded at 11 to complete the starting circuit. A bridging contact 12, mounted on a magnetic plunger 13, is arranged to connect the switch terminals 6 and 8 to close the starting switch when actuated by a solenoid 14, a spring 15 being provided to normally hold the switch open. Means under the control of the operator for energizing the solenoid 14 are provided comprising a lead 16 connected with the battery lead 5, a manual switch 17 connected to the solenoid by a lead 18, and a ground connection 19.

A second plunger of magnetic material 21 is slidably mounted in the solenoid 14 and is provided at its lower end with a cam head 22 which enters the end bearing 23 of the starting motor in position to engage a thrust block 24 bearing on the end of the armature shaft 2. The plunger 21 is normally projected by a spring 25 into the position illustrated in Fig. 1 where the armature shaft has been cammed into its displaced or decentered position, and positively locked therein by engagement of the thrust block 24 with the side of the plunger head 22.

A casing 26 is provided for enclosing and supporting the magnetic starting switch and the shifting and locking means, the casing being attached to the starting motor end bearing 23 in any suitable manner as indicated at 27.

The opposite end of the armature shaft 2 is provided with a smooth reduced extension 28 as illustrated in Fig. 2 on which is slidably journaled a pinion 29 that is adapted to mesh with and rotate a gear 31 of the engine to be started.

A driving sleeve 32 is fixed on the end of the armature shaft as by means of a pin 33, and has slidably journaled thereon a screw shaft 34 retained thereon by a lock ring 35. The screw shaft is yieldably connected to the sleeve for longitudinal and rotary movement by means of a drive spring 36 and anchor plates 37 and 38.

A driving clutch member 39 is threaded on the screw shaft and provided with teeth 41 arranged to engage corresponding teeth 42 on a driven clutch member 43 rigidly mounted as indicated at 44 on the pinion 29. Means for limiting the separation of the clutch members 39, 43 is provided comprising a sleeve 45 fixed to the driving clutch member as shown at 46, and having an inturned flange 47 adapted to engage the driven clutch member when the clutch members are

separated sufficiently to provide clearance between the teeth 41 and 42.

Spring means tending to separate the clutch members is provided in the form of a flat spring member 48 (Fig. 3) attached to the driven clutch member 43 at one end as shown at 49 and tensioned to spring outwardly against the interior of the sleeve 45. Said sleeve is provided with a tapered portion 51 adjacent the spring 48 whereby when the clutch members are engaged the spring bears on the tapered portion and thereby tends to separate the clutch members. The spring 48 is also arranged to serve as a frictional torque transmitting member between the two clutch members whereby a proper amount of control is established to secure reengagement of the clutch members after a false start and to transmit rotation from the pinion to the driving clutch member 39 to secure demeshing of the pinion after the engine has started. The clutch member 39 may be normally retained in its idle position as illustrated by any suitable form of anti-drift detent such as indicated at 50.

Means are preferably provided for yieldably holding the motor armature in centered position during cranking so as to prevent the pinion from floating away from its fully meshed position. As shown in Fig. 1, this may be accomplished by means of a spring-pressed detent 53 mounted in the motor bearing 23 in position to enter a groove 54 in the armature shaft when the armature is in its centered position. When such a detent is used, it may be found desirable to employ a short stiff spring 55 to assist the spring 25 in overcoming the effect of the detent and initiating the displacement of the shaft when the solenoid 14 is deenergized. Spring 55 is preferably made of such length as to be effective only when plunger 21 is near its retracted position, where the effect of the solenoid is sufficiently powerful to insure proper closure of the starting switch 17.

In operation, starting with the parts in the positions illustrated, closure of the manual switch 17 energizes the solenoid 14 which closes the starting switch 7 and also withdraws the plunger 21 against the action of spring 25. The energization of the starting motor causes the armature thereof to center itself, thus moving the armature shaft 2 to the left sufficiently to enter the ends of the teeth of the pinion 29 into the tooth spaces of the engine gear 31. At the same time, rotation of the armature shaft 2 is transmitted through the yielding connection 36, etc., to the screw shaft 34, whereby the driving clutch member 39 is threaded to the left, pushing the pinion along the armature shaft until it engages the shoulder 52 formed by the reduction in diameter thereof. When this occurs, the pinion is fully meshed with the engine gear and the further movement of the driving clutch member 39 causes the teeth 41 thereof to be forced into driving engagement with the teeth 42 of the driven clutch member 43 whereupon a positive driving connection is established from the clutch member 39 to the pinion. The screw shaft 34 is thereby forced backwardly to the right, compressing and loading the drive spring 36 until sufficient torque has been built up to cause rotation of the engine gear to crank the engine.

When the engine fires, the acceleration of the pinion 29 is transmitted through the clutch teeth 42, 41 to the threaded clutch member 39 which consequently threads itself back on the screw shaft 34 and disengages the clutch teeth. The pinion is kept in engagement with the engine

gear 31 by reason of the centered position of the armature shaft 2, and overruns its driving connection freely and quietly since the spring 48 holds the clutch members disengaged.

5 Should the engine fail to continue self-operative, the consequent deceleration of the pinion 29 permits the starting motor to catch up with it, whereupon, due to the frictional drag of the spring 48, the driving clutch member promptly threads 10 itself to the left on the screw shaft, moving the pinion into full mesh and closing the clutch, whereupon cranking is resumed. When the engine is reliably self-operative, the operator opens the manual switch 17, thus deenergizing the solenoid and permitting spring 15 to open the starting switch and spring 25 and 55 to project the plunger 21 so as to overcome the effect of the detent 53 and cam the armature shaft 2 into its 15 idle or displaced position.

20 Although but one embodiment of the invention has been shown and described in detail, it will be understood that other embodiments are possible and that variations in the design and arrangement of the parts may be made without departing from the spirit of the invention as defined in the claims appended hereto.

What is claimed is:

1. In a starting system for internal combustion engines a motor having a longitudinally shiftable armature shaft, a plunger adapted to engage and move said shaft away from its normal running position, a pinion on the shaft having an overrunning clutch connection therewith, and movable with the shaft into and out of mesh with a gear of an engine to be started, and means under the control of the operator for withdrawing said plunger to thereby allow the armature of the motor to freely move to its normal running position.

20 2. In a starting system for internal combustion engines a motor having a longitudinally shiftable armature shaft, a pinion for the shaft having an overrunning connection therewith and movable with the shaft into and out of mesh with a gear of an engine to be started, means for moving the shaft longitudinally and holding it in a position where the pinion may be demeshed from the engine gear, a magnetically operated switch for the starting motor, and means whereby energization 45 of the starting switch moves said holding means to inoperative position to thereby allow the armature of the motor to freely move to its normal running position.

3. In a starting system for internal combustion engines a motor having a longitudinally shiftable armature shaft, a spring-actuated plunger adapted to engage and move said shaft away from its normal running position, a pinion on the shaft having an overrunning clutch connection therewith and movable with the shaft into and out of mesh with a gear of an engine to be started, a switch for controlling the energization of the starting motor, electro-magnetic means for closing the switch, and means actuated by the electro-magnetic means for moving the plunger out of engagement with the shaft.

4. In an engine starter a motor having a longitudinally movable armature shaft, a pinion slidably journaled thereon for movement into and out of mesh with a gear of an engine to be started and having an overrunning driving connection therewith, means including a slidable plunger for moving the armature shaft in a direction to demesh the pinion, spring means for actuating 70 the plunger, a solenoid for retracting the plunger

so as to allow the shaft to float longitudinally, a starting switch, and means including a second plunger actuated by the solenoid for closing the starting switch.

5. An engine starter as set forth in claim 4 in which the plunger which moves the armature shaft is so formed and arranged that final movement of the plunger in the direction to displace the armature shaft causes the plunger to positively lock the shaft in displaced position.

DONALD L. MILLER.
